UNITED STATES PATENT OFFICE.

ANDREW ORTMAYER, OF CHICAGO, ILLINOIS.

HARNESS-SADDLE.

SPECIFICATION forming part of Letters Patent No. 335,142, dated February 2, 1886.

Application filed September 15, 1885. Serial No. 177,157. (No model.)

To all whom it may concern:

Be it known that I, ANDREW ORTMAYER, a citizen of the United States of America, residing at Chicago, in the county of Cook and State of Illinois, have invented certain new and useful Improvements in Harness-Saddles, of which the following, in connection with the accompanying drawings, is a specification.

In the drawings, Figure 1 is a vertical central longitudinal section of a harness-saddle and pad embodying my improvements. Fig. 2 is a section in the plane of the line $x x$ of Fig. 1, viewed in the direction indicated by the arrow there shown. Fig. 3 is a representation of one of the terret-rings, showing its relation to a metallic loop connected thereto, and also showing the relative position of the back-band, and of the roller turning in the said loop. Fig. 4 is a bottom view of the said loop. Fig. 5 is a perspective representation of the yoke of the tree. Fig. 6 is a section in the plane of the line $x' x'$ of Fig. 5. Fig. 7 is a central section from front to rear, taken through the yoke of the tree, and through the saddle and check-hook. Fig. 8 is a detail, in perspective, showing a portion of the metallic loop detached from the terret-ring.

Like letters of reference indicate like parts.

My invention relates, principally, to harness-saddles adapted for use in connection with running or slipping back-bands. It also relates to the means employed for connecting pads removably to saddles of this class.

In the drawings, A represents the yoke of the tree. I make this yoke longer than such parts usually are, or extend its branches, or those parts which form the fork of the yoke, farther from the center than usual. This yoke has in it a long and comparatively wide opening, $a a$, extending nearly the whole length of the yoke, as shown, and $a' a'$ are flanges depending from the yoke along the longitudinal edges of the said opening.

B is a metallic plate extending across the central portion of the yoke, and arranged at the lower edges of the central parts of the flanges $a' a'$, and there connecting the said flanges. This plate B is solid and closes the lower central portion of the opening a .

C C are revolving pins or rollers turning in the flanges $a' a'$, and arranged near the ends of the plate B.

D is a recess at the front central and upper portion of the yoke, and F is a loop in the central rear portion of the yoke. This loop I 55 cast, by preference, in one and the same part or piece with the yoke.

D' is a hole in the forward central portion of the yoke.

E E are the terret-rings, and b b are their 60 spindles or stems, the lower ends of which are screw-threaded, as shown at c c. Next above the screw-threaded portion of the stems b b are collars c c'. This manner of constructing the terrets, however, is not new with 65 me.

F F are metallic loops, applied to the yoke A by means of screws or small bolts d d, passing through the yoke and other parts of the saddle into nuts arranged in the pad, as 70 will hereinafter be more fully explained. The under sides of these loops have therein recesses e e, and G G are nuts arranged in the said recesses. The screw-threaded portions c c pass freely through the loops F F and enter 75 and engage these nuts, thereby connecting the terret-rings securely, but removably, to the said loops, it being understood that the nuts G G are of such form as to be prevented from turning in the recesses e e. It is also to be understood that when the loops F F are applied to the saddle the part of the saddle next below the loops incloses the said nuts in the recesses e e, as will hereinafter more fully appear.

H H are rollers turning in the loops F F. To apply the rollers H H with facility to the loops F F, I cast upon the latter small nibs e e', Fig. 8, and I place the ends of the rollers H H in the sockets or recesses thus formed, 90 and then bend or pinch the nibs e e' together sufficiently to retain the said rollers in place.

I is a jockey, and J is the back-band.

K is the check-hook, and L is the saddle-seat.

M M are skirts.

N is the pad.

The check-hook I apply by arranging its under or lower end in the recesses D, the jockey I arrange to overlap the lower end of the check-hook, and the saddle-seat I arrange, as usual, above or upon the jockey.

O is a screw or bolt passing downward through the saddle, through the jockey,

through the lower end of the check-hook, through the opening D', and through the skirts, and all are bound or fastened together by means of a nut, P, run upon the lower end of the said bolt O. The back-band J lies freely in the channel formed by the opening a, the flanges a', and the plate B, and rests upon the rollers C C. It also passes underneath the rollers H H, and through slits or openings f f in the jockey, and thence down over the skirts. By these means the back-band is allowed to have free movement, and this freedom of movement results mainly for the reason that it passes over the rollers C C and under the rollers H H, as already stated. The back-band is also arranged to move above the plate B, which being made solid, or without openings, and not containing rollers, is not only comparatively strong and durable, but serves as a central brace in the yoke. The back-band is also prevented by the rollers H H from rubbing against the loops F F, and it is thereby prevented from being injured.

The skirts I make, by preference, of heavy leather made in one and the same piece, and of suitable length. In the central portion of the skirts I cut a slot, g, thus making therein a slit or opening sufficiently large to allow the skirts to be fitted to the yoke upon the outer sides of the flanges a' a'. The thickness of the skirts is such as to correspond to the depth of the flanges a' a', and a smooth even surface is thus produced underneath the yoke. This smooth under surface is important, as the parts bearing on the pad are smooth or even, and hence all liability of injury to the animal's back by the movement of the saddle is avoided. The upper side of the yoke is also smooth or even, and when covered by the jockey the saddle therefore has a neat and light appearance.

The skirts I attach to the yoke by means of screws, nails, bolts, or other suitable fastenings, holes h h being made in the yoke for that purpose. The jockey I stitch along its edges to the edges of the skirts, as indicated at i i.

The pad is constructed as a removable and independent part. I prefer to fasten or secure the pad removably under the saddle by means of the same bolts which pass through the loops F F and yoke A, in connection with nuts or burrs Q Q, Fig. 2, secured in the pad. All the parts are thus tightly secured together. I also provide the pad with leather loops R R, one upon each side of the pad, Fig. 1, and through these loops I slip the skirts M M, in order to keep them down upon the pad.

By applying the check-hook in the manner described to the upper side of the yoke only a comparatively small bunch or protuberance 60 results on the under side of the yoke, and the animal is therefore less liable than heretofore to be injured on account of said protuberance.

I have aimed, by the means now described, 65 to so improve harness-saddles that they will be more simple, practicable, and durable than heretofore.

I am aware that harness-saddles have heretofore been combined with slipping or sliding 70 back-straps and anti-friction rollers to aid the free movement of the said strap, and I do not, therefore, here intend to claim the same, broadly; but,

Having thus described my invention, what I 75 claim as new, and desire to secure by Letters Patent, is—

1. The combination, in a harness-saddle, of the yoke A, having therein the opening a, and also having depending flanges a' a' along the 80 longitudinal edges of the said opening or channel, and having also a center plate, B, connecting the lower edges of the said flanges, the pins or rollers C C turning in the said yoke and arranged at the ends of the said plate, 85 and a back-band passing freely through the said channel and over the said plate and rollers, substantially as and for the purposes specified.

2. The combination, with the yoke of a harness-saddle having a sliding or slipping back-band, of the side loops, F F, provided with the revolving pins or rollers H H, and adapted, substantially as described, to receive the terrets and terret-nuts, for the purposes set forth. 90

3. The combination, in a harness-saddle, of a pad provided with loops R R, the side loops, F F, the skirts M M, passing through the loops R R, the yoke, the jockey, the nuts Q Q, located in the said pad, and the screws or bolts 100 d d, passing down through the loops F F and through the jockey, yoke, and skirts into the said nuts, substantially as and for the purposes specified.

In testimony that I claim the foregoing as 105 my own I hereunto affix my signature in presence of two witnesses.

ANDREW ORTMAYER.
